UNITED STATES PATENT OFFICE.

JOHN JAMES GRANT, OF VANCOUVER, BRITISH COLUMBIA, CANADA.

ROCK-DRILLING MACHINE.

Application filed March 2, 1927. Serial No. 172,162.

My invention relates to improvements in rock drilling machines of the reciprocatory and rotary type, such as is described in my previous application for patent in the United States of America, filed May 27th, 1926, under Serial Number 112,070, and is referred to in my subsequent application for patent filed December 20th, 1926, under Serial Number 156,014, to floating tensional devices in conjunction with which the present machine is to be used.

The objects of the invention are to provide means whereby the machine is weighted concentrically so that the reactions imposed upon the machine when reciprocating its rods will be in alignment with the reciprocatory movement and to provide a resilient suspension for the machine. Other objects are to provide an insulation extending the length of the piston, the piston rod and the rifle bar to prevent the absorption of heat by the water passing therethrough from the working spaces of the cylinder. Also to provide means for counterbalancing the weight of the drill rods through the piston; to provide means for cushioning an over-stroke of the piston in either direction, which may occur through a sudden release of gas pressure in the hole drilled, or through the drill breaking through rock or shale into a pocket, and to provide a valve control gear whereby the stroke of the machine may be varied at will and the valve remain full open until the piston approaches the end of its stroke. Other objects of the invention will appear throughout the following description and having reference to the accompanying drawings in which:

Fig. 1 is a vertical sectional view of my invention.

Fig. 2 is a sectional view taken on the line 2—2 of Figure 1, showing the cable suspension of the rods and of the machine.

Fig. 3 is a plan view of the machine taken on the line 3—3 of Figure 1 showing the lower overstroke bumper.

Fig. 4 is an elevational view of the control valve mechanism showing only the portions of the machine to which it is attached.

Fig. 5 is a side view of the valve control mechanism.

Fig. 6 is an enlarged sectional view of the operating valve of the machine.

In the drawings like characters of reference indicate corresponding parts in each figure.

The numeral 1 indicates generally a drilling machine having a cylinder block 2 provided with ported passages 3, 4, and 5, see Figure 5, communicating with a valve chamber 6. Extending from the cylinder block 2 are opposed lugs 7 by which the block is secured to the weight blocks which will be referred to later.

The numerals 8 and 9 indicate a lower cylinder head and an upper cylinder head respectively, which latter is covered with an upper head block 10. The cylinder head 8 is provided with a retaining collar 11 through which, and the upper head block 10, a plurality of spring tensioned rods 12 pass for the purpose of holding the several parts together in the manner usually employed in this type of drilling machine.

The machine 1 is housed in a weight block generally indicated by the numeral 13 which is formed of two portions 14 and 15 and is rebated adjacent their opposing faces so as to form, when connected together, a pair of vertical side grooves 16 which are adapted to engage the guide rails, not shown, of the derrick in which the machine is to be operated. Opposing recesses 17 are formed in the upper portion of each of the halves 14 and 15, which form pockets for receiving the lugs 7 of the cylinder block 2, and bolts 18 are passed through the portions 14 and 15, the recesses 17 and the lugs 7, thus securing the several parts together. Immediately below the lower end of the cylinder block 2, the central portion of the weight block is cut away to define a working space 19 and leaving a pair of side members or legs 20, which are provided intermediate their vertical length with lugs 21, the lower portion of the legs being connected together by a cross member 22 having a recessed circular opening 23 of a greater diameter than any of the machine parts, such as the piston or the drill chuck, that they may be withdrawn therethrough without having recourse to separating the portions 14 and 15 of the

weight block.

weight block 13. Mounted transversely and abutting the lugs 21 is a flange 24 having a recessed circular opening 25 of similar diameter to the opening 23.

- 5 The numeral 26 indicates a piston formed integrally with a piston rod 27 and having at its upper end a rifle bar 28 which is reduced at its upper extremity to cylindrical form as at 29 to serve as a tail rod for the 10 piston. Housed within the upper head block 10 is a ratchet mechanism 30 which engages the rifle bar 28 to impart rotation to the piston and its connected parts on its upward movement, this ratchet mechanism 15 is similar to that usually employed in drilling machines of this type. The lower end of the piston rod 27 is provided with an enlargement 31 forming a chuck for the reception of a drill head 32 to which in turn 20 a tubular drill rod 33 is fitted. A gland 34 is fitted about the cylindrical portion 29 of the rifle bar 28 to prevent the passage of fluid to or from the working spaces of the cylinder.
- 25 The numeral 35 indicates a water inlet header mounted above the gland 34, which is provided with a flange connection 36 to which a water hose, not shown is adapted to be connected. The upper end of the 30 header is fitted with a glanded cover plate 37 through which a sleeve generally indicated by the numeral 38 is endwise movable. The sleeve 38 is provided at its lower extremity with an open sided fitting 39 which 35 is suitably secured to the upper extremity of the cylindrical portion 29 of the rifle bar 28. The piston 26, the piston rod 27 and the rifle bar 28 are provided with an axial passage 40 which is lined with a sleeve 41 having a flange 42 at its lower end, see Figure 1, which is housed in a recess 43 in the chuck 31, wherein it is rendered watertight by suitable washers 44, the upper extremity of the sleeve projects into the fitting 39 and 40 is provided with a gland 45, see Figure 2, to render it watertight and to provide for such endwise movement of the sleeve as may be caused by expansion or contraction. Surrounding the sleeve 41 throughout the length 45 of the piston, piston rod and rifle bar, is a covering 46 of insulating material which serves to prevent the lower temperature of the water flowing through the axial passage 40 from causing condensation within the 50 working spaces of the cylinder 2, when steam or air is used for reciprocating the piston. As a means for supporting the weight of the drill rods connected to the chuck I pass a short length of cable 47 through the sleeve 48, forming an enlargement at its lower end as at 49 to intimately engage the sleeve for the purpose of rendering it watertight and to prevent its removal from the sleeve in an upward direction. This length of cable 47 55 extends a short distance above the sleeve and provided at their lower ends with fastening

enters a bearing housing which is generally indicated by the numeral 49, the cable serving to provide for any reasonable unaligned strain which may occur between the drilling machine and the drill rod suspending cables. 70 The bearing housing is fitted with a heavy ball or other suitable bearing 50 which is provided with a bearing sleeve 51 having an axial bore 52, the upper end of which is outwardly tapered as at 53 to receive a longitudinally divided thimble 54. The upper end of the cable is flared out and babbitted into the thimble as at 55 to secure it against downward movement. The maximum diameter of the flared out portion of the cable, 80 which is held within the thimble 54, is less than the internal diameter of the axial bore 52 of the sleeve 51, so that if occasion should arise where it is desirable to disconnect the cable from the bearing housing 49, the housing is slightly lowered to permit the flared upper portion of the cable to project upwardly through the sleeve, when the longitudinally divided thimble 54 is removed, thus 85 permitting the cable to be withdrawn downwardly from the housing. Extending upwards from the bearing housing is a pair of arms 56 between the upper ends of which a sheave 57 is journaled.

The numeral 58 indicates the bight of a 95 cable 59 the ends of which are led over a head sheave and through a suitable tensioning or counterbalancing device and to a winding drum, not shown, so that the weight carried by the piston is equally supported 100 by the lengths of cable on opposite sides of the sheave. Secured within each of the openings 23 of the lower cross member 22 of the weight block 13, and in the opening 25 of the flange 24 is a bumper generally indicated by the numeral 60, see Figures 1 and 3, which consists of a base 61 formed in two semi-circular portions so that they may be readily withdrawn from the openings to permit the passage of the drill chuck 31 or 105 the piston 26 when desired. The bumper base 61 is recessed as at 62 and is provided with a central aperture 63 through which the piston 27 or the drill rod 33 is endwise movable and a cushion 64 of rubber or other 110 suitable material which is adapted to receive the impact from the chuck 31 or the drill head 32 in the event of the piston travelling beyond a predetermined position from any cause. The suspension of the machine from 115 the head gear of the derrick is by a cable 65 attached at its outer end to a suitable drum and at its inner end to a ring 66 extending from a semi-cylindrical saddle 67. Passing over the ends of the saddle is a 120 pair of short cables 68, the ends of which are connected to a plurality of bolts 69 shown in dotted line in Figure 1, which pass vertically through the weight block and are 125 130

nuts 70, between which and the block compression springs 71 are provided so as to provide a resilient support for the machine permitting it to move slightly in an upward direction without slackening the suspension cables.

The admission of motive fluid to the cylinder is effected through the valve chamber 6, see Figures 5 and 6, to which an inlet pipe 72 is connected. The ported passage 3 leads from the lower side of the valve chamber 6 to the upper end of the cylinder, the ported passage 5 leads from the valve chamber through the cylinder block to a suitable exhaust pipe, not shown, and the ported passage 4 leads from the upper side of the valve chamber to the lower end of the cylinder.

The numeral 73 indicates the valve which consists of a rockingly mounted member having radial vanes 74, 75 and 76. The vanes 74 are apertured to permit the flow of fluid therethrough and are so disposed as to permit of an equalized pressure on opposite sides thereof. The valve 73 is adapted to be rocked between two positions, one being as shown with the vane 75 disposed to admit fluid through the ported passage 4 across the port 3, to the lower end of the cylinder and the vane 76 being so disposed as to direct the flow from the upper portion of the cylinder from the ported passage 3 into the exhaust passage 5, the other position disposes the vane 76 between the entry to ported passages 5 and 3 and the vane 75 between the entry to the ported passage 4 and the inlet pipe 72. The valve 73 is provided with a spindle 77 projecting through suitable glands in the ends of the valve chamber and is fitted with valve levers 78 and 79 respectively, which are set at an angle to each other and in such a position that they alternately assume a substantially horizontal position.

The numeral 80 indicates a bracket extending from the weight block 13 of the machine, in the outer end of which a transverse shaft 81 is suitably journaled. The shaft 81 is provided at its outer end with a sheave 82 by which it is adapted to be rotated by an endless chain 83 extending downwards to within convenient reach of the operator. Extending downwards and lengthwise of the machine is a pair of splined shafts 84 each of which are journalled in the bracket 80 and are fitted at their upper ends with worm gears 85 which are adapted to be rotated in opposite directions by worms 86 upon the shaft 81. The outer or lower end of each of the splined shafts is slidably engaged by a threaded sleeve 87 rotatably mounted in a tubular housing 88. The housings 88 are longitudinally slotted along their outer edges as at 89 and are secured at their lower ends upon the crosshead 90 of a connecting rod 91. The connecting rod 91 is attached

to the outer end of the piston rod 27 by a band 92, which is adapted to encircle the chuck enlargement 31 and to engage a peripheral groove 93 therein, shown in dotted line in Figure 5, so as to permit the piston 70 and chuck to rotate freely and to prevent endwise movement of the chuck within the band. At a point intermediate the chuck and the connecting rod 91 a tubular guide 94 is formed integrally with the band which 75 slidably engages a guide rod 95 extending upwards from the cross member 22 of the weight block 13, thus any tendency of the rotation of the piston to impart a side or 80 rotational strain to the band 92 and its connecting rod 91 is prevented. Suitably mounted upon the face of the weight block 13 is a pair of slide bars 96, which are disposed outwardly of the tubular housings 88. Slidably movable on each of the guide bars are 85 wedge blocks indicated generally by the numerals 97 and 98, each of which consists of a threaded sleeve member 99 engaged by one of the threaded sleeves 87 having a projecting lug 100 projecting through the slot 90 89 of the tubular housing 88 and supporting a wedge member 101 having an inclined face 102 and a vertical face 103. The wedge blocks 97 and 98 are moved lengthwise of the sleeves 87 by the rotation of the shaft 81, 95 which through the worm wheels 85, the worms 86 and the splined shafts 84 impart similar rotation to the sleeves 87, thus causing the wedge blocks to move lengthwise of the threads along the sleeves. Since the 100 shafts 84 rotate in opposite directions, it will be understood that as the shaft 81 is rotated, the wedge blocks 97 and 98 are also caused to approach or recede from each other. As the piston 26 is moved in a downward direction, the wedge blocks 97 and 98 are carried downwards along their slides 96 until the block 97 is brought into contact with the outer end of the lever 78 of the 110 valve 73, which, as the wedge block continues to move, slides along the inclined face 102 thus rocking the valve a sufficient distance to reverse the flow of motive fluid into the cylinder and to start the piston in its return or upward stroke. Near the end of the upward stroke of the piston, the wedge block 98 is brought into contact with the lever 79, swinging it to reverse the valve setting and starting the piston again on its 115 downward stroke. If the piston should travel beyond its predetermined stroke the end of the lever 78 or 79, whichever was last moved by a wedge block will ride along the vertical face 103 of its wedge block, thus holding the valve in set position for the commencement of the return stroke. It will be readily seen that the stroke of the piston may be varied at will by moving the wedge blocks towards or away from each other and that the valve will remain full open from 120 125 130

the commencement of each stroke until the valve is struck by the approaching wedge block as the piston approaches, so that the full force of motive fluid will be applied 5 to the piston throughout its stroke irrespective of the length of such stroke.

In the event of the drill breaking through a structure into a pocket, so that the resistance to its downward movement is suddenly 10 removed and an overstroke of the piston takes place, the chuck 31 will strike the rubber cushion of the bottom bumper, and in case of a sudden release of gas pressure in the hole causing an overstroke of the piston 15 in an upward direction, the chuck 31 will strike the rubber cushion of the upper bumper, thus preventing any damage occurring to the machine while the reactions from such overstroke will be received by the weighted 20 block 13, which as previously described is resiliently supported from the machine cable 65 upon compression springs 71 at the lower end of the bolts 69. The weight of the drill rods being suspended by means of the cable 25 59 passing about the sheave 57, relieves the machine of all unbalanced loading so that great fuel economy is effected in its operation. The provision of the bearing 50 between the sheave 57 and the sleeve 38, attached 30 to the upper end of the rifle bar 28, permits the piston and its associated parts to be rotated by the ratchet mechanism of the drilling machine.

What I claim as my invention is:

35 1. The combination with a rock drilling machine having a cylinder, a piston and a piston rod to which a drill rod is adapted to be connected, and means extending upwards through the cylinder adapted for attachment 40 to a counterbalancing device to support the weight of the drill rod.

2. The combination with a rock drilling machine having a cylinder, having upper and lower heads, a piston having a piston 45 rod at one end to which a drill rod is adapted to be connected and a rifle bar at the other end, a sleeve connected to the outer end of the rifle bar extending beyond the upper head and a cable carried by the sleeve for 50 attachment to a counterbalancing device for supporting the weight of the drill rod.

3. In a rock drilling machine having a cylinder and cylinder heads, an endwise movable and rotatable piston, a piston rod at one end to which a drill rod is adapted to be connected, a tail rod for the piston, means connected to the tail rod and extending through one of the cylinder heads comprising a sleeve having a flexible core and a swivel joint to which a counterbalancing 55 device for supporting the drill rods is adapted to be attached.

4. In a rock drilling machine having a cylinder with upper and lower cylinder 60 heads, a piston therein and having a piston

rod at one end to which a drill rod is adapted to be connected and a tail rod extending through the upper head, of means for connecting the tail rod to a counterbalancing device for supporting the weight of the drill 70 rod, said connecting means comprising a sleeve secured to the tail rod and having a length of cable secured to the sleeve at one end and to a swivel bearing at the other, said connection to the bearing being characterized by an enlargement on the cable housed in a split thimble carried in the bearing whereby the cable may be withdrawn by the removal of the split thimble, said bearing 75 being connected to the counterbalancing 80 device.

5. In a rock drilling machine having a reciprocating piston to which a drill rod is adapted to be connected, and means for suspending the drill rods from a counterbalancing device comprising means extending upwards from the piston through the top of the machine, a rotatable bearing upon said means, a housing for the bearing and a sheave adapted to be carried in the bight of a 90 cable extending from the counterbalancing device.

6. The combination with a rock drilling machine having a cylinder, a piston adapted to be reciprocated by fluid pressure, of a 95 rocking valve having opposed actuating levers for admitting the fluid pressure to opposite ends of the piston, a pair of threaded members reciprocable by the piston carrying wedge blocks adapted to engage 100 the levers at opposite ends of the piston stroke to reverse the flow of fluid pressure to the pistons, and means for moving the wedge blocks in opposite directions along the threaded members, said means comprising 105 a pair of splined shafts upon which the threaded members have sliding movement and a transverse shaft geared to the splined shafts, and means for imparting rotation to the transverse shaft.

7. The combination with a rock drilling machine having a cylinder, a piston, a piston rod, a drill rod, and a chuck connecting the drill rod to the outer end of the piston rod, of a transverse member supported from the cylinder beyond the outer end of the piston stroke, cushioning means carried by the member, and means upon the piston for engaging the cushion on an overstroke of the piston, said cushioning means comprising a transverse member having a central aperture through which the piston rod is adapted to move, a pair of semi-circular base portions detachably carried in said aperture and a resilient member carried upon each of said base portions adapted to receive the impact of the chuck.

8. The combination with a vertically movable weighted block and a rock drilling machine concentrically housed within said 130

weighted block and movable vertically therewith, and cables for supporting said drilling machine and advancing same downwardly toward its work, of a pair of rods extending lengthwise through the block adapted to be connected at their upper ends to the cable supporting means and to be fitted with coil

springs at their lower ends, which springs abut the block whereby the machine and its weight is resiliently supported at its base. 10

Dated at Vancouver, B. C., this 10th day of February, 1927.

JOHN JAMES GRANT.
